DOUBLE LIMIT SWITCH

Malcolm E. Henning, Des Moines, Iowa, assignor
to Penn Electric Switch Co., Des Moines, Iowa,
a corporation of Iowa

Application October 16, 1939. Serial No. 400,084

3 Claims. (Cl. 200—153)

The object of my invention is to provide a double limit switch of simple, durable and comparatively inexpensive construction.

More particularly, it is my object to provide a switch structure for controlling a motor or the like, the switch structure being actuated from a float so that during normal operations of the float the switch is moved to "off" and "on" positions, and when the float lowers to an abnormal position caused by a lack of fluid supplied to the container in which the float is mounted, the float will again operate the switch to "off" position.

More particularly it is my object to provide a switch structure having a switch member movable to "off" and "on" positions and a cam member adapted when in a central position to allow the switch to assume an "on" position, and when rocked to a position on either side of such central position to move the switch member in both instances to "off" position.

Still a further object is to provide a magnet for holding the switch in "on" position as disclosed in the patent issued December 2, 1936 to Albert Penn and bearing No. 1,783,448, the cam of the present invention, when actuating the switch to "off" position acting against the action of such magnet.

Still a further object is to provide a manually operated device for moving the switch to an "on" position after it has been actuated to "off" position caused by an abnormal low position of the float.

With these and other objects in view my invention consists in the construction, arrangement and combination of the parts of my device, whereby the objects contemplated are attained, as hereinafter more fully set forth, pointed out in my claims, and illustrated in the accompanying drawing, in which:

Figure 1 illustrates a sectional view through a storage tank and gravity tank, a pump motor being mounted on the gravity tank and my improved switch structure also mounted thereon.

Figure 2 is an enlarged plan view of the gravity tank with the motor and switch structure thereon, the top of the switch structure being removed and the sides thereof shown in section.

Figure 3 is an enlarged sectional view on the line 3—3 of Figure 2.

Figure 4 is an enlarged sectional view on the line 4—4 of Figure 2; and

Figure 5 is a sectional view on the line 5—5 of Figure 4.

My switch structure is indicated generally by the reference character A and consists of a cas-

ing 10 having a cover plate 12. A supporting bar 14 preferably of insulation is mounted within the casing 10. A bracket 16 is secured to the supporting bar 14 and is provided with a pivot pin 18. The pivot pin 18 has mounted thereon a movable switch arm 20. The switch arm 20 carries a main contact 22 and an auxiliary contact 24. The auxiliary contact 24 is mounted on one end of a leaf spring 26 which has its other end secured to the switch arm 20. The contact 24 extends through an opening in the arm.

When the switch is in "on" position, the contacts 22 and 24 engage contacts 28 and 30. The contacts 28 and 30 are connected together and an electric circuit may be established through the switch by connecting the circuit wires to the contacts 30 and the bracket 16 respectively. A flexible lead 32 extends from the terminal post on the bracket 16 to the switch arm 20 as best shown in Figure 2.

A magnet 34 is mounted on the supporting bar 14 and is adapted to hold the switch arm 20 in "on" position and the magnetic field thereof serves the purpose of blowing out the arc between the contacts 24 and 30 when they are separated. A stop 36 is provided for the switch arm 20 when in "off" position and a bumper spring 38 is mounted on the arm and coacts with the stop 36.

A stub shaft 40 is mounted on the bar 14 and is adapted to be received in a coupling member 42. The coupling member 42 is secured to a float shaft 44 which is adapted to oscillate. The float shaft 44 extends through a packing nut 36 on a float arm casing 48.

The float arm casing 48 is adapted to be secured to the top of a liquid container 50. A float arm 52 is secured to the float arm shaft 44 within the casing 48 and is connected by means of a rod 54 with a float 56. Stop collars 58 and 60 are secured to the rod 54 with which the float 56 coacts in its movements up and down as caused by the rise and fall of the level of the liquid 62 within the container 50.

A pin 63 extends from the switch arm 20 and is located above the float shaft 44 (see Figure 3). The pin 63 has a head 64 of insulation. A cam lever 66 is adapted to coact with the pin 64 and is secured to the coupling 42. An insulating disk 65 is carried by the switch arm 20 and interposed between the cam lever 66 and the switch arm to prevent a short circuit between these parts. The cam lever 66 is provided with a low point 66a and inclined cam surfaces 66b and 66c. As shown in Figure 3 when the low point 66a of the cam lever 110

66 registers with the pin 64, the switch structure is in "on" position. When either of the cam surfaces 66b or 66c coat with the pin 64, however, as shown by dotted lines and when the float shaft 44 is rocked in opposite directions as shown by dotted lines in Figure 4, the switch arm 20 in each instance is moved to "off" position.

My switch structure is adapted to be used in connection with a pump motor 68 or other electrical devices for controlling the same depending upon the level of the liquid in the container 50. The container 50 in the illustration of Figure 1 is a gravity tank the liquid 62 of which is oil to be supplied to a burner. The liquid 62 is supplied to the container 50 from a storage tank 70. A supply pipe 72 leads from a check valve in the bottom of the tank 70 to a pump structure 74 connected with the pump motor 68. The discharge of the pump 74 is indicated at 76 and is located within the container 50 whereby oil pumped from the storage tank 70 enters the container 50.

Practical operation

In the operation of my device in the installation illustrated, the switch is shown in "on" position so that the pump 74 will be operated by the motor 68 for pumping liquid into the container 50. The level of the liquid will accordingly rise and carry the float 56 upwardly with it until the float engages the collar 58 after which the rod 54 will be raised to the dotted line upper position shown in Figure 4. This causes the cam member 66 to assume a corresponding position as shown in dotted lines in Figure 3 so that the cam surface 66b thereof will move the switch arm 20 to "off" position as shown in dotted lines. The motor 68 will immediately stop and as the liquid in the container 50 is used, the level thereof will lower until the parts assume the full line position shown in Figure 2. The motor and pump will immediately begin to operate for again filling the container 50.

However, if there is no oil in the tank 70 to be pumped into the container 50, use of the oil from the container 50 will keep on lowering the level thereof while the pump is operating without drawing any oil into the container 50. When the level of the liquid 62 consequently reaches a low position as shown by the lower dotted level in Figure 4, the float 56 will engage the collar 60 and the weight of the float will move the rod 54 downwardly and the arm 52 to its lower dotted position. This causes the cam 66 to be rotated so that the cam surface 66c engages the pin 64 for moving the switch arm to "off" position so that the pump does not continue to operate indefinitely without any supply of oil being provided for it.

When the tank 70 is again refilled a push button 78 on the switch structure is pushed downwardly to the dotted line position shown in Figure 3 for moving the switch arm 20 to "on" position. The switch is held in this position until the level of the liquid 62 is sufficiently high to cause the float 56 to float. The push button 78 may then be released and will move upwardly due to a spring 80 thereunder.

The push button 78 is connected by a rod 82

with an insulating button 84 which engages the bumper spring 38 of the switch arm 20. A sleeve 86 is provided on the lid 12 of the switch casing through which the rod 82 is slidably mounted.

Although I have illustrated my double limit switch in connection with a float device so that the switch will be turned off when the level of a liquid lowers to an abnormal position, the cam arm 52 may be connected with any other type of motive device desired, such as a diaphragm so as to control electric devices according to pressure or temperature instead of liquid level. The illustration in Figure 1 is merely to show how the device may be applied to a storage tank and a gravity tank for an oil burner.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In an automatic control switch, a movable two position switch member, magnetic means for normally constraining said switch member to one of its positions, a rock shaft, a member thereon of resilient material bent to form a depression and a riser portion on each side of said depression, condition responsive means for automatically rocking said rock shaft, an abutment on said switch arm, said depression and said riser portions being adapted to register therewith for resiliently operating said switch member to allow it to remain in said mentioned position when the depression registers therewith and to cause it to move to the other of its positions when either of said riser portions register therewith.

2. In a double limit control switch, a movable two position switch member, magnetic means for normally constraining said switch member to one of its positions, a rock shaft, a resilient cam lever thereon bent to form a depression and a riser portion on each side of said depression, a single abutment on said switch member, said depression and said riser portions each being adapted to register therewith for operating said switch member to allow it to remain in said mentioned position when the depression registers therewith and to cause it to move to the other of its positions when either of said riser portions register therewith.

3. In a double limit control switch, a movable two position switch member, magnetic means for normally constraining said switch member to one of its positions, a resilient rockable member having a depression and a riser portion on each side of said depression, an abutment on said switch arm, said depression and said riser portions being adapted to register therewith for operating said switch member to allow it to remain in said mentioned position when the depression registers therewith and to cause it to move under the resilient tension of said rockable member to the other of its positions when either of said riser portions register therewith.

MALCOLM E. HENNING.
